AUTOMATIC WORK ABRADING APPARATUS

Rolland G. Hall, Yalesville, Conn., and Stewart M. Hill, Sherrill, N. Y., assignors to R. Wallace & Sons Manufacturing Company, Wallingford, Conn., a corporation

Application July 10, 1948, Serial No. 38,066

9 Claims. (Cl. 51—84)

1

This invention relates to apparatus for finishing opposite surfaces or edges of manufactured articles, and more especially, though not exclusively, to apparatus for trimming and/or buffing the opposite edges of table flatware, such as the customarily butt-joined side edges of knife handles, for instance.

It is the primary aim and object of the present invention to provide apparatus of this type which will perform simultaneously on a large number of identical articles, such as knife handles, in such fashion that the opposite edges of the knife handles are operated on under the control of a master cam which not only prevents excessive abrading of these handles, but also preserves their correct contours and even corrects their contours where they are slightly off.

It is another important object of the present invention to provide apparatus of this type which is fully automatic in its operation and has operating cycles of predetermined duration that are started on momentary manipulation by an operator of a control element of the apparatus.

It is another important object of the present invention to provide apparatus of this type in which during an operating cycle thereof the work to be abraded is first moved from a retracted position into operative engagement with oppositely spinning abrading or operating wheels, is then repeatedly reciprocated while remaining in operative engagement with the operating wheels, and is finally returned to retracted position for removal from the apparatus without interference from the spinning wheels.

It is another important object of the present invention to provide apparatus of this kind which, by a simple manipulation of a control element of the apparatus and quick and facile exchange of the operating wheels thereof, is adaptable either to a trimming operation or to a buffing operation, the latter to include the application of a buffing compound to the buffing wheels at the beginning of each buffing cycle of the apparatus.

It is another important object of the present invention to provide apparatus of this type with interchangeable work racks so that one rack may be loaded with a multitude of knife handles to be operated on, while another loaded rack is in the apparatus and the knife handles thereon are being operated on.

It is another important object of the present invention to provide in apparatus of this type for movement of the work to be operated on in transverse directions between the fast spinning trimming or buffing wheels, depending on the type

2

of operation to be performed, so as to obtain optimum performance of these wheels on the work during an operating cycle of minimum duration.

5 It is another important object of the present invention to operate the present apparatus principally hydraulically for attaining simplicity of construction of the apparatus, and accomplishing its efficient operation with a minimum number of movable parts and a minimum of wear between the parts.

10 It is another important object of the present invention to provide the present apparatus with controls that render the latter foolproof in its operation, and permit instantaneous interruption for any length of time of an operating cycle of the apparatus by the operator for the purpose of inspecting, or making adjustments on, the work or the operating parts of the apparatus.

15 The above and other objects, features and advantages of the present invention will be more fully understood from the following description considered in connection with the accompanying illustrative drawings.

20 In the drawings:

Fig. 1 is a front perspective of apparatus embodying the present invention;

Fig. 2 is a rear perspective of the apparatus;

Fig. 3 is a front elevation of the apparatus;

25 Fig. 4 is a side elevation, partly in section, of the apparatus, as viewed in the direction of the arrow 4 in Fig. 3;

30 Figs. 5 and 6 are vertical sections through the apparatus, taken substantially on the lines 5—5 and 6—6, respectively, of Fig. 3;

35 Fig. 7 is a fragmentary section through the apparatus, taken substantially on the line 7—7 of Fig. 6;

Fig. 8 is a fragmentary section taken on the line

40 8—8 of Fig. 3;

Figs. 9 and 10 are sections taken on the lines 9—9 and 10—10, respectively, of Fig. 4;

45 Fig. 11 is an enlarged, fragmentary section through the apparatus, taken substantially on the line 11—11 of Fig. 3;

Fig. 12 is a front elevation of a work-rack used in the present apparatus;

Fig. 13 is a section taken on the line 13—13 of Fig. 12;

50 Fig. 14 shows diagrammatically, in side elevation, certain cooperating parts of the apparatus shown in Fig. 5;

Fig. 15 is a plan view of the parts shown in Fig. 14;

55 Figs. 16 and 17 are views similar to Fig. 14, but

showing the parts in different operating positions;

Fig. 18 is a wiring diagram of the electrical controls of the present apparatus; and

Fig. 19 is a hydraulic diagram of certain fluid-pressure operated devices of the present apparatus.

Briefly, the instant apparatus is adapted to perform, by way of example, on the opposite side edges *e* of hollow knife handles *k* (Figs. 12 and 13) which are customarily formed of complementary halves that are soldered along the seam *s*. In order to render the seams *s* to all intents and purposes invisible on the finished knife handle, they are subjected first to a trimming operation and then to a buffing operation. In this connection, it may be stated in advance that the present apparatus is so constructed as to be adaptable for trimming operation or for buffing operation, or both.

The instant apparatus comprises a base frame 30 which is in the form of a housing having a front wall 32, side walls 34, and a rear wall 36 which leaves an opening 38 in the rear of the frame for ready access to the interior thereof. The front and rear walls 32 and 36 are lined at the top with angles 40 (Figs. 5 and 6) on which is mounted in any suitable manner a platform 42. The side walls 34 of the base frame 30 may also be provided at the top with inwardly extending flanges 44 (Fig. 7) which serve as additional mountings for the platform 42. Mounted in and on the base frame 30 are, as herein-after described, the operating wheels A and their respective drives B (Figs. 5, 6 and 7). Bolted at 50, or otherwise secured, to the opposite side walls 34 of the base frame 30 are standards 52, respectively, which are joined at the top by a brace 54 in the form of a plate that may be connected with the standards 52 by angles 56 (Fig. 2). Mounted on the braced standards 52 are, as herein-after described, a work carrier C (Figs. 1, 3 and 6), carrier operating devices D (Figs. 1, 2 and 8), controls E for the operating wheels (Figs. 1 and 4), a buffing compound applicator F (Figs. 1, 3 and 11); electrical controls G of apparatus (Figs. 1, 3 and 18), and a hydraulic control system H (Fig. 19).

Operating wheels A

As mentioned above, the operating wheels 60 (Figs. 6 and 7) may be either trimming wheels or buffing wheels. Each of these wheels 60 comprises a multiplicity of fabric disks which are mounted on a shaft 62, and are preferably cemented together in their side-by-side relation so as to constitute a fairly rigid wheel. If the wheels 60 are to be used for trimming purposes, their peripheries are preferably coated with a grinding compound which lasts for a considerable number of trimming cycles of the apparatus before recoating is required. If the wheels 60 are to be used for buffing purposes, there is applied in the present instance, a buffing compound to their peripheries at the start of each buffing cycle of the apparatus.

Journaled in suitable bearing brackets 70 on the base frame 30 are two countershafts 72 (Figs. 6 and 7), each of which carries near its ends arms 74 that extend through transverse slots 76 in the platform 42 of the base frame 30 (Figs. 5 and 7). The arms 74 on each shaft 72, together with removably mounted caps 78 thereon, provide spaced journal bearings for the shaft 62 of an operating wheel 60. The shafts 72 are

rocked in opposite directions so as to swing the operating wheels 60, in the course of their performance, to and from each other in a manner and by means hereinafter described. The peripheries of the wheels 60 extend into the interior of the base frame 30 through a cutout 41 in the platform 42, said cutout 41 being of sufficient width (Fig. 6) to permit the abovementioned swinging motions of the wheels 60. Since the wheels 60 perform an abrading operation regardless of whether they are used for trimming or for buffing, there is provided underneath these wheels a pan 80 (Figs. 6 and 7), which is suitably secured to the platform 42, and receives all waste matter dropping from the work and from the wheels 60. The pan 80 has at the rear of the apparatus an outlet 82 which may, through a suitable conduit (not shown), communicate with any conventional suction device for drawing the accumulated waste matter from the pan 80. Suitably hinged at 84 on the platform 42 are guards 86 over the exposed peripheries of the wheels 60 (Figs. 1 and 6), these guards serving not only to keep the operator's hands from the wheels 60, but also to direct all waste matter from the work and operating wheels into the pan 80 provided therefor.

Wheel drives B

Two opposed ends of the shafts 62 of the operating wheels 60 extend beyond the adjacent sides of the base frame 30 and there carry pulleys 90, respectively (Fig. 3). The pulley 90' on the rear wheel 60' (Figs. 6 and 7) is drivingly connected by belts 92 with a pulley 94 on the shaft 96 of an electric motor 98 which is suitably mounted on a bracket 100 that is, in turn, mounted for swinging movement at 102 in a bearing bracket 104 on the front wall 32 of the base frame 30. The bracket 100 is provided with an upward extension 106 in which is swivelled the shank 108 of a nut 110 with which a spindle 112 is in threaded engagement. The spindle 112 has any conventional universal mounting in a bracket 113 on the rear wall 36 of the base frame 30, and carries a hand wheel 115. Thus, the tension of the belts 92 may be regulated by turning the hand wheel 114 in the proper direction and, in consequence, swinging the motor-carrying bracket 100 on its pivot axis 102. The pulley 90'' on the front wheel 60'' is drivingly connected by belts 120 with a pulley 122 on the shaft 124 of another electric motor 126 which, as shown in Fig. 5, is carried by a mounting bracket 128, journaled at 130 in a bearing bracket 132 on the rear wall 36 of the base frame 30. Swivelled in an upward extension 134 of the mounting bracket 128 is the shank 135 of a nut 136 which is in threaded engagement with a spindle 138 that has any conventional universal mounting in a bracket 140 on the rear wall 36 of the base frame 30 and carries a hand wheel 142, the latter to be manipulated for regulating the tension of the belts 120, as will be readily understood. Thus, the wheels 60 are individually driven from their respective motors 98 and 126, in opposite directions, and more particularly in the direction of the arrows 146 and 148, respectively, in Fig. 6.

Work carrier C

Referring now more particularly to Figs. 1 and 3, the work carrier comprises, in the present instance, a vertically reciprocating frame 150 and an oscillatory frame 152. The reciprocating frame 150 comprises opposite sliding brackets

5

154 and 156 and connecting cross bars 158. The brackets 154 and 156 are slideable on vertical guide posts 155 and 157, respectively, which are mounted on the adjacent standards 52, respectively, through intermediation of mounting brackets 160 (Figs. 1 to 5). Thus, the sliding brackets 154, 156 and the connecting cross bars 158 form a single unit which is vertically reciprocable on the guide posts 155 and 157.

The oscillatory frame 152 comprises side members 162 and connecting cross bars 164, which together form a single unit. The side members 162 are reclined for sliding movement on the cross bars 158 of the reciprocating frame 150, thus permitting oscillation of the frame 152 on the other frame 150 transversely of the direction of reciprocation of the latter frame.

Preferably, there are interposed between the slides 154 and 156 and the adjacent brackets 160, respectively, bellows 168 of rubber or the like which surround the guide posts 155 and 157, respectively, and contract and expand on reciprocation of the frame 150, as will be readily understood. These bellows 168 protect the guide posts 155 and 157 from dust and other foreign matter. The length of the guide post 155 between the lateral lugs 170 of the slide 154 is also protected from dust and other foreign matter by a sleeve 172 which surrounds post 155 and is interposed between the lugs 170 in the manner best shown in Fig. 3. Those portions of the cross bars 158 of the frame 150 on which the side members 162 of the oscillatory frame 152 oscillate, are preferably also protected from dust and other foreign matter by contractable and expansible bellows 174 which, as best shown in Fig. 3, are anchored with their ends on fixed collars 176 on the cross bars 158 and on similar collars 178 on the side members 162, respectively.

The present apparatus is also equipped with one or more detachable work racks 180, one of which is shown in Figs. 1 and 12. The work rack 180 is in the form of a U-shaped bar having opposite legs 182 and a connecting yoke 184. The legs 182 of the work rack are provided with elongated slots 186 by means of which the work rack is suspended from headed pins 188 on the lower ends of the side members 162 of the oscillatory frame 152 (Fig. 6). Suitably secured in the yoke 184 of the work rack 180 are a multiplicity of blades 190 which serve as holders for the knife handles *k* to be operated on. More particularly, the knife handles are inserted over the blades 190 (Figs. 12 and 13) and are held thereon in upright position (Fig. 13). When suspended from the oscillatory frame 152, as described, the work rack 180 is located in the median vertical plane between the wheels 60 as shown in Fig. 6, so that the knife handles *k* on the work rack will be evenly contacted on opposite sides by the operating wheels 60 on vertical reciprocation of the work rack with the frames 150 and 152.

Operating devices D for work carrier

Referring now to Figs. 1, 3 and 6, there is mounted at 192 on the plate 54 between the standards 52 a hydraulic cylinder 194 in which is slideable a double-acting piston 195 (Fig. 19) the rod 196 of which is connected at 198 with a bracket 200 (Fig. 6) which is carried by the cross bars 158 of the frame 150, and serves to impart the reciprocating motion of the piston 195 in the "work-rack" cylinder 194 to the frame 150.

The prime mover for the oscillation of the

6

frame 152 is an hydraulic motor 202 (Figs. 2, 6 and 8) which is carried by a housing 204 that is, in turn, mounted in any suitable manner on the plate 54 between the standards 52. The hydraulic motor 202 is as of a well known type and requires no detailed disclosure. For the present purpose, it is sufficient to understand that the drive shaft 206 of the motor 202 turns in one direction on the passage of a liquid under pressure through the motor. The housing 204 is closed at its open front by a cover 208, and houses a gear 210 (Fig. 8) which is mounted on the motor shaft 206 and is in permanent mesh with another gear 212 on a shaft 214. Shaft 214 is journaled in the housing 204 and cover 208, and carries externally of the housing 204 a disk 216 having a crank pin 218 which is received in a vertical groove 220 in the rear of the side member 162 of the oscillatory frame 152. Thus, the frame 152 and, hence, also the work rack 180 thereon will, on operation of the hydraulic motor 202, be oscillated on the frame 150, and such oscillation of the frame 152 may take place uninterruptedly during reciprocation of the other frame 150.

Controls E for operating wheels

Referring now more particularly to Figs. 1, 3 and 4, the rock shafts 72 of the operating wheels 60 have extensions 232 beyond one side of the base frame 30 and there carry arms 234, respectively, which are provided at adjacent ends with followers 236, respectively, adapted to cooperate with master cams 238, respectively. The opposite ends of the arms 234 are pivotally connected at 240 with an extension 242 on a cylinder 244 and a piston rod 246, respectively. Rod 246 is carried by a double-acting piston in the cylinder 244, the opposite ends of which communicate with a source of liquid under pressure through conduits 248 and 250, respectively. When liquid under pressure is admitted through conduit 250 into the right-hand end of the cylinder 244, as viewed in Fig. 4, the piston therein is forced to the left, with the result that the lower ends of the arms 234 are forced apart and the followers 236 on the other ends of the arms 234 are forced into engagement with their respective master cams 238. Conversely, the followers 236 on the arms 234 are disengaged from their respective master cams 238 when liquid under pressure is admitted through conduit 248.

The master cams 238 are accurately positioned on dowel pins 251 on opposite slides 252 and 254, respectively, and are held thereon by screws 253 (Figs. 4 and 10). The slides 252 and 254 are guided for movement to and from each other in a horizontal dovetail groove 256 in a slide 258 (Fig. 10) which is, in turn, guided for vertical movement in a dovetail groove 260 in the sliding bracket 154 of the reciprocating frame 150 (Figs. 1, 3, 4 and 9). The cam-carrying slides 252 and 254 are in threaded engagement with oppositely threaded lengths 262 and 264, respectively, of a spindle 266 which is suitably journaled in forwardly projecting lugs 268 of the vertical slide 258 and carries at one end a hand wheel 270 with which to turn the spindle 266 and thereby adjust the spacing of the master cams 238 in accordance with the width of the knife handles 70 to be operated on by the operating wheels 60. The vertical slide 258 is in threaded engagement with a spindle 272 which is held axially immovable in a projecting lug 274 on the adjacent bracket 154 and carries thereabove a hand wheel 75 276 with which to turn the spindle 272 and there-

by adjust the master cams 238 in correct vertical position.

The active faces 280 of the master cams 238 are machined so that intermediate lengths thereof, corresponding to the length of a knife handle to be operated on by the wheels 60, has the correct contour of this knife handle, and the master cams 238 are so adjusted, through manipulation of the hand wheels 270 and 276, that the correct contour portions of these master cams cooperate with the followers 236 on the arms 234 when the corresponding contour portions of the knife handles on the mounted work rack 180 are in operative engagement with the wheels 60. Thus, the wheels 60, be they trimming or buffing wheels, are, on reciprocation of the work between the wheel 60, positively moved to and from each other in such manner that their peripheries follow the correct contour of the work, thereby preventing excessive abrading of the knife handles, and even correcting the contours of the latter where slightly off.

Buffing compound applicator F

Referring now to Figs. 1, 3 and 11, there is shown a buffing compound applicator 290 which, at the beginning of each buffing cycle only of the apparatus, travels along the operating wheels 60, first in one direction and then in the opposite direction, and discharges the compound in relatively liquous form on the adjacent peripheries of the wheels 60. The applicator 290 is mounted at 292 on a cross head 294 which is slidable axially of the wheels 60 on rods 296 that are mounted with their ends in opposite brackets 298 and 300 on the standards 52, respectively (see also Fig. 7). Journaled with its ends in the bracket 300 and in a cover 302 on the opposite bracket 298, respectively, is a spindle 304 which is in threaded engagement with a bushing 306 in the cross head 294 so that, on rotation of the spindle 304 in opposite directions, the cross head 294 is moved in opposite directions on the rods 296. One end of the spindle 304 (Fig. 7) is coupled at 308 to the drive shaft 310 of a reversible hydraulic motor 312 which is suitably mounted on the outside of the adjacent standard 52. The motor is of a conventional type which reverses the direction of rotation of its drive shaft on reversing the flow of a liquid under pressure through the motor.

The compound applicator 290 comprises, in the present instance, two sprayers 222 which have nozzles 224 through which buffing compound is directed against the peripheries of the operating wheels 60, respectively (Fig. 11). The sprayers 222 are of a conventional and well known type and do not require a detailed disclosure. Each sprayer contains a buffing compound in liquous form which, on the flow of compressed air through a Venturi passage in the sprayer is forced from the latter through the nozzles 224 thereof. Compressed air is conducted from an air valve 223 to the sprayers 222 through a flexible hose connection 225 and tubes 226 and 227, respectively. The air valve 223, which is mounted on a bracket 228 on one of the standards 52 (Figs. 2 and 7), is, through a conduit (not shown), in permanent communication with a source of compressed air. The air valve 223 has a control element 229 which is turnable into positions to open and close the valve. The control element 229 of the air valve 223 is provided with a laterally projecting finger 230 which cooperates with a pin 231 on the cross head 294 for opening and closing the valve. As previously stated, the compound applicator 290

is, at the beginning of each buffing cycle of the apparatus, moved from the home position shown in Fig. 3, first to the left and then back into home position, the work rack 180 in the apparatus being then in its uppermost position so as not to interfere with the described travel of the compound applicator. Immediately after the compound applicator 290 starts to move from home position, the pin 231 on the cross head 294 engages the finger 230 and turns the control element 229 of the air valve 223 into open position in which compressed air passes through the latter to the sprayers 222 for the forced discharge of buffing compound therefrom. The control element 229 of the air valve 223 is, on being turned into open position by the pin 231 as described, backed up against a spring (not shown) in the valve which, after the passage of the cross head 294, will return the control element 229 into a position in which the air valve 223 is still open and the finger 230 is in the path of movement of the pin 231 on the following return movement of the cross head 294 and compound applicator 290 into home position. Thus, the pin 231 on the cross head 294 will turn the control element 229 into valve-closing position shortly before the cross head 294 and compound applicator 290 return to home position. The control element 229 is, on being turned into valve-closing position by the pin 231 as described, backed up against a spring (not shown) in the valve which, after passage of the cross head 294, turns the control element 229 into a position in which the air valve 223 is still closed and the finger 230 is in the path of movement of the pin 231 for the next performance of the compound applicator 290 at the start of the next buffing cycle of the apparatus.

Electrical controls G of apparatus

The heretofore mentioned hydraulically operated devices 194, 202, 244, and 312 require for their operation a liquid, such as oil, which is put under pressure in a manner hereinafter described by a pump 320 (Fig. 19) that is driven by an electric motor 322 (Figs. 2 and 4) which is mounted on the bottom of the base frame 30. The apparatus further comprises an electric fan motor 324 (Figs. 2 and 18) which is used in conjunction with a cooler 326 in which the hot oil is on its circuitous path through the apparatus effectively cooled so as to preserve its maximum operating efficiency. Thus, the present apparatus has four electric motors of which two drive the operating wheels 60, one drives the pump 320 and another operates the fan which is associated with the oil-cooling unit 326. The apparatus further comprises solenoid-operated valves 330 and 332 (Fig. 19) which are mounted on the plate 54 between the standards 52, and are preferably enclosed in covers 334, respectively (Figs. 1 and 3). The solenoid valve 330 is one of several controls for the admission of oil under pressure to, or its interception from, the work-rack cylinder 194, while the other solenoid valve 332 controls the admission of oil under pressure in opposite directions to the hydraulic motor 312 which drives the feed spindle 304 for the compound applicator 290. Solenoid valve 330 has windings 336 and 338 (Fig. 18) and the other solenoid valve 332 has windings 340 and 342.

Reference is now had to the wiring diagram in Fig. 18 which discloses the electrical controls for the above-mentioned electric motors 98, 126, 322 and 324, as well as for the solenoid coils 336, 338 and 340, 342. These controls include a "Start"

switch 344, a "Stop" switch 346, a "Pump-wheel" switch 348, a "Raise-stop-auto" switch 350, and a timer 352, all as shown in Figs. 1, 3 and 18.

The sole current source used in the present apparatus is a 3-phase current represented in the wiring diagram by the lines L1, L2 and L3. To start the apparatus, the operator throws switch 348 into the "Pump" position in order to connect the pump motor 322 and fan motor 324 with the electric power source and build up oil under pressure in the various oil lines to be described in the apparatus, before the wheel motors 98 and 126 are permitted to run and before the work is permitted to come into operative engagement with the wheels 60. By shifting the switch 348 into the "Pump" position as described, there is closed a starting circuit of a holding coil 360 which is part of a conventional magnetic starter switch 362. Coil 360 will, on energization, close all normally open pairs of contacts 364 of the starter switch 362. The starting circuit of the holding coil 360 of the starter switch comprises line L1, a lead 366, the normally closed stop switch 346, a lead 368, the bridged contacts *a* and *b* of switch 348, leads 370 and 372 with the normally closed switch 374 in the latter lead, holding coil 360, lead 375 with the interposed, normally closed switch 376, and line L2. With the contact pairs 364 in the starter switch 362 closed in consequence of the energization of the holding coil 360, the lines L1, L2 and L3 are connected with the pump motor 322 through the starter switch 362 in a self-evident manner. On closure of the magnetic starter switch 362 as described, the primary 380 of a step-down transformer 382 is energized by virtue of its connection through the leads 384 with the then charged terminal points 386, respectively of the starter switch 362. The fan motor 324 will run simultaneously with the pump motor 322, this by virtue of the fact that the secondary 388 of the transformer 382 is connected with the fan motor 324 through the leads 390 and 392. Thus, while current of fairly high voltage in the lines L1 to L3 may be used for the pump motor 322 and also for the wheel motors 98 and 126, there is available at the secondary 388 of the transformer current of lower voltage which is suitable for the fan motor 324 and the solenoid windings 336, 338 and 340, 342.

The operator next throws switch 348 into the "Wheel" position in which the contacts *c* and *d* thereof are bridged by the movable switch blade 394. In doing so, the above described starting circuit of the holding coil 360 of the starter switch 362 is interrupted at the contacts *a* and *b* of switch 348, but a holding circuit of the coil 360 has also been closed immediately on closing the starting circuit thereof. This holding circuit of the coil 360 comprises line L1, lead 366, stop switch 346, lead 368, a lead 530, the then magnetically closed switch 364, lead 372 with the normally closed switch 374, coil 360, lead 375 with the interposed normally closed switch 376 and line L2. With the switch 348 in "Wheel" position, the circuit of a holding coil 396 of another magnetic switch 298 is closed, whereby all normally open pairs of contacts 400 of the latter switch are closed. The circuit of the holding coil 396 comprises line L1, switch 362, leads 402 and 404, the then bridged contacts *c* and *d* of switch 348, leads 406 and 408 with the normally closed switch 410 in the latter lead, holding coil 396, lead 412 with the interposed, normally closed switch 414, lead 416, starter switch 362 and line

L2. Thus, on closure of the described circuit of the holding coil 396 of the magnetic switch 398, in consequence of the shift of switch 348 into the "Wheel" position, the wheel motors 98 and 126 are connected in a self-evident manner with the power lines L1 to L3 through the closed magnetic switches 362 and 398. It follows from the preceding that the wheel motors 98 and 126 may operate only after the pump and fan motors 322 and 324 operate, for the circuits of the latter motors are closed on closure of the magnetic switch 362, while the circuits of the former motors are closed on closure of both magnetic switches 362 and 398 only, and switch 398 can be closed only after switch 362 is closed.

At this stage in an initial operating cycle of the apparatus, the pump motor 322, fan motor 324 and the wheel motors 98 and 126 are operating, but the loaded work rack 180 in the apparatus is still in the raised position shown in Fig. 6. Assuming that the apparatus is to perform a buffing operation, a manual switch 420 has then previously been closed so that the compound applicator may next perform its designated function of spraying the peripheries of the operating wheels 60 with buffing compound. Hence, with the switch 420 closed, manual operation of the start switch 344 at this time will start a performance of the compound applicator 290. Depression for a brief period of time of the start switch 344 into position in which the same bridges the contacts *a'* and *b'* thereof results in closure of a starting circuit of the solenoid winding 340, which circuit comprises one side *x* of the secondary 388 of the transformer, a lead 424, a contact 426 of the timer 352, a lead 428 with its intermediate connection 429 with the solenoid windings 336 and 338, solenoid winding 340, leads 430 and 432, the momentarily bridged contacts *a'* and *b'* of the start switch 344, a lead 434, the closed switch 420, a lead 436, and the other side *y* of the secondary 388 of the transformer. Simultaneously with the closure of this starting circuit of the solenoid coil 340, there is also closed a starting circuit for a relay 438, the latter circuit comprising side *x* of the secondary 388 of the transformer, lead 424, contact 426 of timer 352, a lead 440, relay 438, a lead 442, a normally closed snap switch 444, a lead 446, leads 430 and 432, the momentarily bridged contacts *a'* and *b'* of the start switch 344, lead 434, closed switch 420, lead 436, and the other side *y* of the secondary 388 of the transformer.

As previously mentioned, the compound applicator 290 assumes, in the home or idle position of the apparatus, the position shown in Figs. 1 and 3, in which a pin 450 on the cross head 294 (Fig. 7) holds the movable blade 452 of a snap switch 454 (Fig. 18) in engagement with the contact 456 thereof against the normal tendency of the blade 452 to spring into engagement with the other contact 458 thereof. The switch 454 is conveniently mounted on one of the standards 52 (Figs. 2 and 7), and is accessible to the pin 450 on the cross head 294 through an opening (not shown) in said standard. As soon as the above-described starting circuit of the solenoid winding 340 is closed, the compound applicator will, in a manner hereinafter described, move immediately to the left as viewed in Figs. 1 and 3, i. e. away from the snap switch 454, so that the blade 452 thereof will spring from the full-line position into the dotted-line position shown in Fig. 18, while the operator still holds the start switch 344 depressed. The described starting circuit of

the relay 438 is interrupted when the operator releases the start switch 344, but the blade 452 of the snap switch 454 has in the meantime assumed the dotted-line position in Fig. 18 in which it connects the contacts 458 and 460 which are in a holding circuit of the relay 438. This holding circuit comprises side *x* of the secondary 388 of the transformer, lead 424, contact 426 of timer 352, lead 440, relay 438, lead 442, switch 444, leads 446 and 430, the normally disengaged contacts 464 and 466 of a switch 467 which has also normally open contacts 472 and 474, and of which the former contacts are now engaged, and the latter contacts disengaged, due to the energization of relay 438 on previous closure of the starting circuit thereof, a lead 468, the then bridged contacts 458 and 460 of switch 454, a lead 470, and the other side *y* of the secondary 388 of the transformer. Simultaneously with the described closure of the holding circuit of the relay 438, there is also closed a holding circuit of the solenoid winding 340, the latter circuit comprising side *x* of the secondary 388 of the transformer, lead 424, contact 426 of timer 352, lead 428 with its intermediate connection 429 with the solenoid windings 336 and 338, solenoid winding 340, lead 430, the engaged contacts 464 and 466 of switch 467, lead 468, switch 454, lead 470, and the other side *y* of the secondary 388 of the transformer. Thus, the holding circuit of the solenoid winding 340 is closed while the compound applicator 290 travels initially along the wheels 60 to the left as shown in Figs. 1 and 3, or to the right as viewed in Fig. 2. Toward the end of the described initial travel of the compound applicator 290, a pin 480 on the cross head 294 (Figs. 1, 2 and 7) engages and opens the snap switch 444, which is mounted on the outside of one of the standards 52 and is accessible through an opening 482 in the latter (Figs. 2 and 6). When switch 444 is thus opened at the end of the initial travel of the compound applicator 290, the above-described holding circuits of the relay 438 and solenoid winding 340 are opened and the circuit of the solenoid winding 342 is simultaneously closed for the return travel of the compound applicator 290 into home position, as hereinafter described. This latter circuit comprises side *x* of the secondary 388 of the transformer, lead 424, contact 426 of timer 352, lead 428 with its intermediate connection 429 with the solenoid windings 336 and 338, solenoid winding 342, a lead 490, the then normally engaged contacts 472 and 474 of switch 467, lead 468, the then bridged contacts 458 and 460 of switch 454, lead 470, and the other side *y* of the secondary 388 of the transformer. Energization of the solenoid winding 342 will, as hereinafter more fully described, result in return travel of the compound applicator 290 into home position. When the compound applicator reaches home position, the pin 450 on the cross head 294 (Fig. 7) returns blade 452 of switch 454 into the full line position shown in Fig. 18, opening thereby the circuit of the solenoid winding 342, with the result that the compound applicator comes to a stop in home position. The peripheries of the turning wheels 60 having now been sprayed with buffing compound, the work rack 180, which is normally in its uppermost position (Fig. 6) starts to descend immediately when the compound applicator reaches home position and actuates switch 454 in the described manner, i. e., forces switch blade 452 into the full-line position shown in Fig. 18. Prior to this stage in an operating cycle of the apparatus, the operator has shifted

switch 350 to the "Auto" position, thereby conditioning the circuit of the winding 336 of the solenoid valve 339 for closure immediately when the returning compound applicator shifts switch 454 into the full-line position shown in Fig. 18. The circuit of the solenoid winding 336 comprises side *x* of the secondary 388 of the transformer, lead 424, contact 426 of the timer 352, lead 423, solenoid winding 336, a lead 494, the then connected contacts 496 and 498 of the timer 352, a lead 500, a contact 502 of the timer 352, a lead 504, the then bridged contacts *c'* and *d'* of switch 350, a lead 506, the normally bridged contacts *a''* and *b''* of switch 344, a lead 508, the then bridged contacts 456 and 460 of switch 454, lead 470, and the other side *y* of the secondary 388 of the transformer. Closure of this latter circuit causes a shift of the solenoid valve 339 from a neutral position to be described into the full-line position shown in Fig. 19, in which the same is conditioned for power reciprocation of the piston 195 in the work-rack cylinder 194 in a manner hereinafter described. The subsequent reversal at the end of each stroke of the piston 195 in the work rack cylinder 194 is under the control of a pilot valve 640 which is operated by the reciprocating frame 150 in a manner hereinafter described. The timer 352 may be preset to any predetermined time period, within limits, which is chosen for a buffering cycle. A detailed disclosure of the timer 352 is not deemed essential for an understanding of the present invention, and is, hence, omitted, particularly since this timer is of a conventional type and its construction forms no part of the present invention. However, if the timer is set for a buffering cycle and, hence, for a longer duration of the cycle, the contacts 496 and 498 thereof will be disconnected, and will, in a manner conventional for this timer, be connected only after the compound applicator 290 has in the course of its performance in a buffering cycle, moved from home position. In this way, closure of the solenoid winding 336 and, hence, reciprocation of the work rack piston 195, are prevented at the beginning of a buffering cycle of the apparatus before the compound applicator moves from home position. If the apparatus is conditioned for trimming operation, the timer is, due to the cut-out of the operation of the compound applicator, set for a shorter time period, at which setting the contacts 496 and 498 will be connected for immediate closure of the solenoid winding 336 and according reciprocation of the work rack piston 195 at the beginning of each trimming cycle. Whether the timer is set for buffering performance or for trimming performance of the apparatus, the timer will, at the end of each cycle be returned to its preset position for the next cycle. At the end of the predetermined time period for which the timer 352 is set, the contacts 496 and 498 of the timer are disconnected and the contacts 493 and 516 thereof are connected, opening thereby the above-described circuit of the solenoid winding 336 and simultaneously closing the circuit of the solenoid winding 338 of the solenoid valve 339. This latter circuit comprises side *x* of the secondary 388 of the transformer, lead 424, contact 426 of timer 352, lead 428, solenoid winding 338, a lead 520, the then connected contacts 516 and 498 of the timer 352, lead 500, contact 502 of the timer, lead 504, the then bridged contacts *c'*, *d'* of switch 350, lead 506, the normally bridged contacts *a''*, *b''* of switch 344, lead 508, the then bridged contacts 456 and 460 of switch 454, lead

470, and the other side *y* of the secondary 388 of the transformer. Closure of the circuit of the solenoid winding 338 will result in ascent of the work rack 180 to its uppermost position in which it will remain, without being oscillated, until the operator starts the next operating cycle by depressing the start switch 344, provided the stop switch 346 has not been opened in the meantime by the operator for a purpose hereinafter described.

The switches 348 and 350 having been left in their respective "Wheel" and "Auto" positions, and the work rack 180 having been removed from the apparatus, and either reloaded and returned in the apparatus, or replaced by another loaded rack, the operator need merely depress the start switch 344 in order to start another buffering cycle of the apparatus.

If the present apparatus is to be used for trimming the side edges of knife handles, the buffering wheels 60 are replaced by trimming wheels, though for large production it is preferable to use one or more apparatus permanently for trimming purposes, and one or more apparatus for buffering purposes. As previously mentioned, the compound applicator is not used when the apparatus is used for trimming purposes. In that event, the compound applicator 290 is rendered inoperative by opening the manual switch 420 (Fig. 18). With the switch 420 open, the operator may start the trimming cycle by depressing the start switch 344, after first shifting switch 348 into the "Pump" position and then into "Wheel" position, and also shifting switch 350 into the "Auto" position. The operating cycle that will then take place is in all respects like the above-described initial buffering cycle, except that the solenoid windings 340 and 342 will not be energized due to the opening of the switch 420. By failing to energize the solenoid windings 340 and 342, the solenoid valve 332 will throughout the cycle remain in a neutral position to be described, with the result that the compound applicator 290 will remain in its home position throughout the cycle and the solenoid winding 336 is energized on depression of the start switch 344, causing immediate reciprocation of the work in the apparatus.

Once the apparatus has been started and the switches 348 and 350 have, in the course of the initial operating cycle, been shifted to their respective "Wheel" and "Auto" positions, as described, and are left in these positions, repeat cycles may be started by merely depressing each time the start switch 344. Repeat cycles differ from an initial cycle in that neither operation of the pump 320 nor rotation of the operating wheels 60 need be started at the beginning of each repeat cycle, for the pump continues to operate and the wheels continue to rotate during intermittent stops of the apparatus between successive repeat cycles. This is due to the fact that the circuit of the pump motor 322 is closed as long as the magnetic starter switch 362 is closed, and the latter remains closed until the stop switch 346 is depressed, this by virtue of the fact that switch 346 affords the only means with which to interrupt the previously described holding circuit of the holding coil 360 of the starter switch 362. Continued rotation of the operating wheels 60 during intermittent stops of the apparatus between successive repeat cycles is due to the fact that the circuit of the wheel motors 98 and 126 are closed as long as the starter switch 362 and magnetic switch 398 are

closed, and these motor circuits may be interrupted only by depressing the stop switch 346 or by shifting switch 348 from "Wheel" position. The apparatus may be brought to a full stop only on depression of the stop switch 346, which results in de-energization of the holding coil 360 of the starter switch 362 and corresponding opening of the latter. Opening of the starter switch 362 interrupts not only the circuit of the pump motor 322, but also the circuit of the holding coil 396 of the magnetic switch 398, resulting in interruption of the circuits of the wheel motors 98 and 126. The circuits of the remaining electrical devices of the apparatus are then also interrupted by virtue of the fact that depression of the stop switch 346 results in opening of the starter switch 362 and, hence, in interruption of the circuit of the primary 380 of the transformer 382. Thus, the instant apparatus may be stopped immediately and at any time on mere momentary depression of the stop switch 346, as will be readily understood.

As previously mentioned and as further explained hereinafter, the energized winding 336 of the solenoid valve 330 effects operation of the piston in the work rack cylinder 194 and of the work-oscillating motor 202. However, when both windings 336 and 338 of the solenoid valve 330 are de-energized, the latter assumes a neutral position to be described in which the piston in the work rack cylinder 194 is retained in its uppermost position and the work-oscillating motor 202 is hydraulically locked, with the result that the work rack 180 in the apparatus neither reciprocates nor oscillates. Hence, if switch 350 is, at any time during an operating cycle of the apparatus, switched from "Auto" position to "Stop" position, solenoid valve 330 will immediately shift into its neutral position, with the result that the work rack 180 will be brought to an immediate stop in the same position which it assumes at the time switch 350 is thus shifted into "Stop" position. This is highly expedient where the operator detects in the course of an operating cycle of the apparatus any condition which may be, or threatens to be, harmful to the work or to the operating parts of the apparatus.

The work rack 180 may, during an interruption in an operating cycle, be raised to its uppermost position and there held for any length of time, by shifting switch 350 into the "Raise" position and thereby closing another circuit of the solenoid winding 338, causing movement of the piston in the work-rack cylinder 194 into its uppermost position, as previously described. The latter circuit of the solenoid winding 338 is, in the "Raise" position of switch 350, closed by way of side *x* of the secondary 388 of the transformer, lead 424, contact 426 of the timer 352, lead 428, solenoid winding 338, lead 520, a lead 540, the then bridged contacts *c'* and *d'* of switch 350, a lead 542, lead 596, switch 344, lead 508, the bridged contacts 456 and 460 of switch 454, lead 470, and the other side *y* of the secondary 388 of the transformer.

Hydraulic control system H

Assuming that the apparatus is to perform a buffering cycle and has been started as described hereinbefore, the previously described electrical controls will, due to the energization of the solenoid winding 340, cause a shift of the solenoid valve 332 from a neutral position to be described into the full-line position shown in Fig. 19.

When the solenoid valve 332 assumes this full-line position, oil under pressure will flow through the reversible hydraulic motor 312 in one direction in which to cause movement of the compound applicator 290 in the initial direction along the peripheries of the operating wheels 60. Oil under pressure will then be forced from the pump 320 in an oil reservoir 560 through conduits 550 and 552 and a preferably interposed pressure-regulating needle valve 554 to and through the solenoid valve 332, thence through a conduit 556 to the hydraulic motor 312 from where the oil is returned to the reservoir 560 by way of conduit 562, solenoid valve 332, conduit 564 and conduit 566 with the interposed cooling unit 326. Oil under pressure will thus flow through the motor 312 until the compound applicator 290 reaches the end of its initial travel and opens the snap switch 444, closing thereby the circuit of the solenoid winding 342 and accordingly effecting a shift of the solenoid valve 332 from the full-line position into the dot-and-dash line position shown in Fig. 19. In thus shifting the solenoid valve 332, oil under pressure in the conduits 550 and 552 will then pass through the solenoid valve 332 and through conduit 562 into the motor 312 in a direction opposite to the previous flow of the oil therethrough, the oil then being returned from the motor 312 to the oil reservoir 560 through conduit 556, solenoid valve 332 and conduits 564 and 566. When oil under pressure flows in this fashion through the hydraulic motor 312, the latter causes return movement of the compound applicator 290 into its home position.

As soon as the compound applicator 290 reaches home position, the circuit of the winding 342 of the solenoid valve 332 is interrupted and the latter returns to its neutral position in which the motor 312 is hydraulically locked as hereinafter described. The circuit of the winding 336 of the solenoid valve 330 is closed simultaneously with the opening of the circuit of the solenoid winding 342, causing thereby a shift of the solenoid valve 330 from a neutral position to be described into the full-line position shown in Fig. 19, in which it provides communication between the conduits 550 and 568, that carry oil under pressure from the pump 320, and a conduit 570 which leads to one end of a control valve 572 in which the admitted oil forces the sliding valve 574 into the full-line end position shown in Fig. 19, against the tendency of a spring 576 to move the valve 574 into the opposite end position. When the valve 574 is shifted into this full-line position, oil under pressure from the pump 320 is immediately admitted to the top end of the work rack cylinder 194 by way of conduit 550, a conduit 580, a flow control valve 582, conduits 584 and 586, a control valve 588 (assuming at this time full-line position in Fig. 19 for down stroke of work rack piston 195 as hereinafter described), conduit 590, control valve 572, and conduit 592. Oil under pressure is at the same time admitted to the lower end of the work rack cylinder 194 by way of conduit 584 and a preferably interposed pressure control valve 594. Inasmuch as the exposed cross-sectional area of the piston 195 in the work-rack cylinder 194 is larger at the top than at the bottom thereof, it stands to reason that the total pressure of the oil against the top face 598 of the piston 195 exceeds the total pressure of the oil against the bottom face 600 thereof, with the result that the piston 195 descends and carries the work on the rack 100 between the operating

wheels 60. The oil in the lower end of the cylinder 194 is, during the descent of the piston 195 therein, by-passed to the top end of the cylinder by way of conduit 584 and interposed valve 594, conduit 586, valve 588, conduit 590, valve 572 and conduit 592.

Simultaneously with the start of the work reciprocation, oil under pressure is also permitted to flow from the pump 320 through the work-oscillating motor 282 by way of the conduits 550 and 580, a conduit 602, a flow control valve 604, a conduit 606, and the motor 282, thence through conduits 608 and 610, solenoid valve 330, and conduits 612, 614 and 566 to the oil reservoir 560. Thus, the work rack 100 starts to oscillate at the same time it starts to descend on its first work stroke. Simultaneously with the shift of the solenoid valve 330 into the full-line position shown in Fig. 19, oil under pressure from the pump is also admitted to the active side of the wheel pressure cylinder 244 by way of conduit 550, a conduit 620, a flow control valve 622, a conduit 624, a pressure control valve 626, and the flexible hose connection 250. The oil in the opposite side of the same cylinder 244 is then permitted to return to the oil reservoir 560 by way of the flexible hose connection 248, conduit 610, solenoid valve 330, and conduits 612, 614 and 566. Thus, on energization of the winding 336 in each operating

cycle of the apparatus, and according shift of the solenoid valve 330 into the full-line position shown in Fig. 19, the cylinders 194 and 244 and the hydraulic motor 282 simultaneously receive oil under pressure, with the result that the work-rack piston 195 will descend for the first time in a cycle, the cylinder 244 and piston therein will bring the operating wheels 60 under the control of the master cams 238, and the hydraulic motor 282 will oscillate the work.

Suitably mounted on vertically adjustable brackets 632 and 633 on the slide 156 of the reciprocating frame 150 (Fig. 5) are two blocks 634, respectively, having projecting lugs 636 and 638, respectively, which are adapted to operate the previously mentioned pilot valve 640 (see also Figs. 14 to 17). The brackets 632 and 633 are slideable in a dove-tail groove 635 in the slide 156 (Fig. 5) and are in threaded engagement with axially immovable spindles 637 and 639, respectively, on the slide 156, said spindles 637 and 639 having knobs 641 and 643, respectively, with which to turn said spindles and thereby adjust the vertical position of the respective brackets 632 and 633. The pilot valve 640 comprises a casing 642 (Fig. 19) and a rotary valve element 644 therein. The valve element 642 extends to the outside of the valve casing 640 and there carries a valve actuator 646 having angularly spaced fingers 648 and 650 which are also spaced horizontally from each other as shown in Fig. 15. The finger 648 of the valve actuator 646 is in operative alignment with the lower lug 638, while the other finger 650 of the valve actuator is in operative alignment with the upper lug 636. As previously mentioned, the pilot valve 640 is adapted to control the flow of oil to and from the top end of the work-rack cylinder 194 so as to reverse the piston 195 therein at the end of each down or upstroke thereof, and this control is operative throughout the predetermined time period which the preset timer 352 allows for the reciprocation of the work in an operating cycle of the apparatus. The vertical adjustability of the lugs 636 and 638 in the apparatus also affords a convenient means not only to regulate the stroke

of the piston 195 in the work-rack cylinder 194 for the reciprocation of the work, but also to confine the reciprocation of the piston 195 to different regions within the work-rack cylinder 194. Thus, by properly adjusting the lugs 636 and 638, the work will, after its initial descent from uppermost position, be reciprocated through partial strokes of such length that the work will remain in operative engagement with the operating wheels 60 throughout its reciprocation, and will at the end of its predetermined cycle of reciprocation be raised to its uppermost position in which it is out of operative engagement with the wheels 60 and may be removed from the apparatus. Also, the described adjustability of the lugs 636 and 638 adapts the apparatus for trimming or buffing knife handles of different length, as will be readily understood.

The angular position of the valve actuator 646 and, hence, of the rotary element 644 in the pilot valve 640 depends solely on the preceding downward or upward stroke of the reciprocatory frame 150. Thus, when the work-carrying frame 150 descends, the upper lug 636 thereon will, near the lower limit of the down stroke of said frame as determined by the adjustment of lug 636, engage the finger 650 of the valve actuator 646 and turn the latter from the position shown in Fig. 14 into that shown in Fig. 15, in which finger 650 is out of the path of the lug 636, and the other finger 648 is in the path of the other lug 638 on the following upstroke of the frame 150. The lug 638 will engage finger 648 of the valve actuator 646, and turn the latter back to the position shown in Fig. 17, when the work-carrying frame 150 is near the upper limit of its following partial upstroke as determined by the adjustment of the lug 638. In the position of the pilot valve 640 as shown in Figs. 14, 17 and 19, the same provides communication between the pump 320 and the left hand end of valve 588 (Fig. 19) by way of conduit 550, a passage 660 in the valve element 644 and a conduit 662. The right hand end of valve 588 is then exhausted by way of conduit 664, another passage 661 through the rotary element 644 in the pilot valve 640, a conduit 670, and the conduits 614 and 566. In consequence of the described admittance of oil under pressure to the valves 588, the latter assumes the full-line position shown in Fig. 19, in which oil under pressure is admitted to the top end of the work-rack cylinder 194, as previously described. Hence, the work-rack piston 195 will, in an operating cycle of the apparatus, descend after each partial upstroke thereof, every time the pilot valve 640 is shifted into the position shown in Figs. 14 and 19, except when the latter is thus shifted for the last time in each operating cycle, as will become obvious hereinafter. When the lug 636 shifts the pilot valve 640 into the position shown in Fig. 16 on each descent of the work-carrying frame 150, the valve element 644 of the pilot valve will intercept communication between the conduits 550 and 662, and instead provide communication between conduit 550 and another conduit 664 which leads to the right hand end of the valve 588 as viewed in Fig. 19. Admittance of oil under pressure to the right hand end of the valve 588 results in a shift of the valve element 666 therein from the full-line position into the dot-and-dash line position. The left hand end of the valve 588 is then exhausted by way of conduit 662, passage 661 in the rotary element 644 of the pilot valve 640, and conduits 670, 614 and 566. The valve element 666 of valve 588 now

being in the dot-and-dash line position in Fig. 19, the same permits the exhaust of the top end of the work-rack cylinder 194, resulting in an upstroke of the piston 195 therein because the lower end of the cylinder remains subjected to oil under pressure. The upper end of the work-rack cylinder 194 is then exhausted by way of conduit 592, valve 572, conduit 590, valve 588, and conduit 566. When the ascending frame 150 approaches the adjusted upper limit of its partial stroke, the lug 638 engages the aligned finger 648 of the valve actuator 646 and turns the pilot valve 640 back to the position shown in Figs. 14 and 19, resulting in the next descent of the work. The work-rack piston 195, and, hence, the frames 150 and 152 as well as the work rack 180, are thus reciprocated until the timer 352 terminates the operating cycle of the apparatus by effecting closure of the circuit of the winding 338 of the solenoid valve 330. When this occurs, the solenoid valve 330 is shifted into the dot-and-dash line position shown in Fig. 19, in which oil under pressure in the conduit 568 is admitted through the valve 330 and the conduits 610 and 608 to the work-oscillating motor 202, thereby immediately locking the latter hydraulically. Oil under pressure in the conduit 610 is then also admitted through the hose connection 248 to the wheel pressure cylinder 244 for effecting separation of the operating wheels 60 and according disengagement of the followers on the arms 234 from their respective master cams 238. The other side of the wheel-pressure cylinder 244 is then exhausted by way of the hose connection 250, valve 626, a conduit 672 and conduit 566, the sprung-urged valve element 627 in the valve 626 being then subjected at the bottom to oil under pressure in the conduit 610 and, in consequence, raised sufficiently to provide communication between the hose connection 250 and the conduit 672. Energization of winding 338 of the solenoid valve 330 at the end of an operating cycle of the apparatus and the corresponding shift of the solenoid valve 330 into the dot-and-dash line position shown in Fig. 19, results also in the exhaust of the left hand end of the valve 572, so that the latter may, under the force of the spring 576 move into the dot-and-dash line position in Fig. 19. Valve 572 is thus exhausted by way of conduit 570, solenoid valve 330, and conduits 612, 614 and 566. Valve 572 now assuming the dot-and-dash line position shown in Fig. 19, the top end of the work-rack cylinder 194 is exhausted by way of conduit 592, valve 572, a conduit 678 and conduit 566. The lower end of the cylinder 194 is subjected to oil under pressure as long as the pump 320 operates, wherefore the work-rack piston 195 and parts connected therewith are returned to their uppermost position at the end of each operating cycle of the apparatus. Should the operator fully stop the apparatus at the end of a day's performance or at any other time, by depressing the stop switch 346, the oil in the various lines supplied by the pump 320 will then be no longer under pressure, with the result that the valve element 680 in the valve 594 is sprung-urged into a position in which it blocks conduit 584, whereby the oil in the lower end of the work rack cylinder 194 becomes locked therein and retains the piston 195 in its uppermost position while the apparatus is stopped completely.

Whenever the windings 340 and 342 of the solenoid valve 332 are de-energized, the sliding valve element 684 thereof is urged by balanced springs (not shown) into the before-mentioned neutral

position in which its lands 682 block the adjacent ends of the conduits 556 and 562, respectively, thereby maintaining the hydraulic motor 312 for the compound applicator 290 hydraulically locked. The sliding valve element 686 in the other solenoid valve 330 is, whenever both windings 336 and 338 thereof are de-energized, forced by balanced springs (not shown) into the before-mentioned neutral position in which the lands 670 of the valve element 686 block the adjacent ends of the conduits 610 and 570, respectively, and thus intercept communication between these conduits and the conduit 568 which is in open communication with the pump 320.

Resume of operation

Assuming that the present apparatus is at a complete standstill and that a loaded work rack 180 is suspended from the oscillatory frame 152 in the manner best shown in Fig. 6, and further assuming that the apparatus is set for a buffing cycle, the operator will then initiate the cycle by first throwing switch 348 into "Pump" position in order to effect closure of the magnetic starter switch 362 and, hence, closure of the circuit of the pump motor 322, all as previously described. Operation of the pump 320 results in the build-up of oil under pressure in the various oil lines that lead to the hydraulic devices of the apparatus. However, these oil lines are at this initial stage in an operating cycle effectively blocked from their respective hydraulic devices so that the continuously flowing oil from the pump is at this time returned to the oil reservoir 560 past a check valve 700 and through a conduit 702. Simultaneously with the shift by the operator of the switch 348 into "Pump" position and according closure of the magnetic starter switch 362, the circuit of the motor 324 for the oil cooler 326 is also closed.

The operator next shifts switch 348 from the "Pump" position into the "Wheel" position, effecting thereby immediate closure of the magnetic switch 398. The closed magnetic switch 398, in turn, closes the circuits of the wheel motors 98 and 126, as previously described. The circuit of the primary 380 of the transformer 382 having previously been closed on closure of the magnetic starter switch 362, the start switch 344 may, for the performance of the compound applicator 290, now be depressed for a brief time period. Brief depression of the start switch 344 results in consecutive closure of the previously described starting and holding circuits of the winding 340 of the solenoid valve 332, causing thereby a shift of the latter into the full-line position shown in Fig. 19, in which it directs the flow of oil under pressure through the hydraulic motor 312 in such direction that the latter moves the compound applicator 290 in its initial direction to the left as viewed in Figs. 1 and 3. Shortly after the compound applicator commenced to travel in the initial direction, the air valve 223 (Figs. 1, 3 and 11) is opened by the pin 231 on the cross head 294, admitting thereby air under pressure to the sprayers 222 of the applicator and causing the same to discharge buffing compound onto the revolving wheels 60. When the compound applicator 290 reaches the end of its initial travel, the pin 480 on the cross head 294 opens the snap switch 444 (Figs. 7 and 18) and, consequently, the holding circuit of the winding 340 of the solenoid valve 332. Opening of the holding circuit of the solenoid winding 340 results in immediate closure of the circuit of the

other winding 342 of the solenoid valve 332 in the previously described manner, causing thereby a shift of the latter into the dot-and-dash line position shown in Fig. 19 in which the same directs oil under pressure through the hydraulic motor 312 in the opposite direction. The hydraulic motor 312 then causes return movement of the compound applicator 290 into home position. Shortly before the compound applicator reaches home position, the pin 231 on the cross head 294 shifts the air valve 223 into closed position so as to withhold further compressed air from the sprayers 222 and render the latter inoperative.

The returning compound applicator 290 forces switch 454 into the full-line position shown in Fig. 18, and thereby closes the circuit of the winding 336 of the solenoid valve 330, provided switch 350 has previously been shifted to "Auto" position. Immediately on closure of the circuit of the winding 336 of the solenoid valve 330, the latter is shifted into the full-line position shown in Fig. 19, in which the same effects swinging movement of the operating wheels 60 and their follower arms 234 into operative relation with the master cams 238, and further effects reciprocation and oscillation of the work for a predetermined time period during which the operating wheels 60 perform the desired buffing operation on the opposite side edges of the knife handles while the same remain in operative engagement with the wheels 60, as previously fully explained. More particularly, the solenoid valve 330 will, when in the full-line position shown in Fig. 19, effect a shift of the control valve 572 into the full-line position, in which oil under pressure is admitted through the latter to the top end of the work rack cylinder 194 to effect the first and full down stroke of the work from uppermost position. The solenoid valve 330 will then also provide communication between the exhaust conduits 608 and 610 of the work oscillating motor 202 and the exhaust conduits 612, 614 and 566, thereby unlocking the motor 202 and permitting the same to be operated by oil under pressure flowing through the conduits 550, 580 and 602, flow-control valve 604 and conduit 606 (Fig. 19). The solenoid valve 330 will then also permit the exhaust of the right-hand side of the wheel pressure cylinder 244 (Fig. 19), with the result that oil under pressure will now be admitted into the other side of the cylinder 244 and the follower arms 234 of the operating wheels 60 will be brought into operative relation with the master cams 238. The lower end of the work-rack cylinder 194 is permanently subjected to oil under pressure from the pump 320 as long as the latter operates, as has been previously explained. However, on initial admission of oil under pressure to the upper end of the cylinder 194, in consequence of the shift of the valve 572 into the full-line position shown in Fig. 19, the oil displaced from the lower end of the cylinder 194 by the descending piston 195 therein is bypassed to the top end of the same cylinder through conduit 534 with the interposed valve 594, conduit 586, valve 588, conduit 590, valve 572, and conduit 592.

The pilot valve 640 assumes the position shown in Figs. 14 and 19 when the frame 150 with the work thereon starts to descend from uppermost position for the first and only time in an operating cycle of the apparatus. This is due to the fact that the pilot valve has been shifted into this position by the frame 150 on its ascent into uppermost position at the end of the preceding

cycle of operation of the apparatus. Toward the end of the initial and full downward stroke of the frame 150, the lug 636 thereon will shift the pilot valve 640 from the position shown in Fig. 14 into the position shown in Fig. 16, in which the same admits oil under pressure from the conduit 550 through the conduit 664 into the right hand end of the valve 588, causing thereby a shift of the latter from the full-line position into the dot-and-dash line position shown in Fig. 19, in which the top end of the work-rack cylinder 194 is permitted to exhaust by way of conduit 592, valve 572, conduit 590, valve 588, and conduit 566. The work-rack piston 195 will then reverse its stroke and move upwardly, this by virtue of the fact that the lower end of the work-rack cylinder 194 is continuously subjected to oil under pressure from the pump 320. When the frame then nears the adjusted limit of its partial upstroke, the lug 638 thereon will engage the finger 648 of the valve actuator 646 and turn the pilot valve 640 back into the position shown in Figs. 14 and 19, in which the same effects a renewed down stroke of the work-rack piston 195, as will be readily understood. Thus, the work will continue to reciprocate and oscillate while remaining in operative engagement with the wheels 60, until the timer 352 opens in the previously described manner the circuit of the winding 336 of the solenoid valve 330, and simultaneously closes the circuit of the winding 338 thereof. Closure of the circuit of the winding 338 causes a shift of the solenoid valve 330 from the full-line position into the dot-and-dash line position (Fig. 19) in which conduit 570 is exhausted by way of valve 330 and the conduits 612, 614 and 566, with the result that element 574 in the valve 572 is spring-urged into the dot-and-dash line position (Fig. 19) in which the top end of the work-rack cylinder 194 is permitted to exhaust by way of conduit 592, valve 572, and conduits 678 and 566. When in the dot-and-dash line position, the solenoid valve 330 also provides communication between the conduit 568 that carries oil under pressure, and the conduit 610 and branch conduit 608, thereby causing the work-oscillating motor 202 to become hydraulically locked, and causing the wheel pressure cylinder 244 and piston therein to withdraw the follower arms 234 of the operating wheels 60 from their respective master cams 238, all as previously described in detail.

A repeat buffing cycle of the apparatus may, after replacement of the work therein, be started by depressing the start switch 344. The repeat cycle that will then take place starts immediately with a performance of the compound applicator 290, and the cycle itself is exactly the same as the previously described initial cycle starting with the performance of the compound applicator thereof. Immediate performance of the compound applicator in this and any following repeat cycle is due to the fact that the pump motor 324 and the wheel motors 98 and 126 keep on running between intermittent stops of the apparatus, and will stop only if the operator depresses the stop switch 346, all as previously described. Hence, the present apparatus may perform as many repeat cycles as are desired, each repeat cycle to be started by merely depressing the start switch 344.

In order to bring the apparatus to a full stop at the end of a day's performance or at any other time, the operator need merely depress the stop switch 346 momentarily, as will be readily under-

stood from the preceding description. If the operator should, in the course of an operating cycle of the apparatus, detect faulty performance of the operating wheels 60 on the work, or notice any other abnormal condition that may be, or threatens to be, harmful to the work or to the operating parts of the apparatus, the operator may arrest the reciprocation and oscillation of the work in any instant position, by shifting switch 350 from "Auto" position to "Stop" position. In the latter event, it may be desired to bring the work in the apparatus to its uppermost position, in which case the operator need merely shift switch 250 into the "Raise" position.

If the present apparatus is to be used for trimming purposes, the buffing wheels are replaced by trimming wheels, and switch 420 is opened. The opening of the switch 420 eliminates in each trimming cycle a performance of the compound applicator 290. With this single exception, a trimming cycle of the apparatus is exactly like a buffing cycle thereof.

While we have shown and described a preferred embodiment of our invention, it will be understood that various changes may be made in the present invention without departing from the underlying idea or principles of the invention within the scope of the appended claims.

Having thus described our invention, what we claim and desire to secure by Letters Patent is:

1. In apparatus of the character described having a rotary buffing wheel, and a carrier removably holding work and being reciprocable to move the work to and from operative engagement with said wheel, the combination of a rotatably mounted threaded spindle extending substantially parallel to said wheel, a buffering compound applicator non-rotatably mounted on, and in threaded engagement with, said spindle so as to move axially on said spindle when the latter rotates, and means for driving said spindle in either direction to move said applicator thereon along said wheel in compound-applying relation therewith.
2. The combination in apparatus as set forth in claim 1, in which said spindle driving means comprise a reversible hydraulic motor drivingly connected with said spindle, and control means operable to direct fluid under pressure through said motor in opposite directions, respectively.
3. The combination in apparatus as set forth in claim 1, in which said spindle driving means comprise a reversible hydraulic motor drivingly connected with said spindle, and a valve normally assuming a neutral position and shiftable into two operating positions in which to direct fluid pressure through said motor in opposite directions, respectively, said valve intercepting the flow of fluid under pressure to said motor when in its neutral position.
4. The combination in apparatus as set forth in claim 1, in which said spindle driving means comprise a reversible hydraulic motor drivingly connected with said spindle, a valve normally assuming a neutral position and shiftable into two operating positions in which to direct fluid under pressure through said motor in opposite directions, respectively, said valve intercepting the flow of fluid under pressure to said motor when in its neutral position, solenoid windings adapted, when energized, to shift said valve into said operating positions, respectively, and a separate circuit including a switch, for each solenoid winding.
5. In apparatus of the character described

having a rotary buffing wheel; and a carrier removably holding work and being reciprocable to move the work to and from operative engagement with said wheel, the combination of a buffing compound applicator, means for moving said applicator to and from a home position adjacent one end of said wheel in a direction longitudinally of, and in compound-applying relation with, said wheel, power means for reciprocating said carrier and control means including two normally open switches for causing, on closure of said switches, a cycle of operation of said power means during which to move said carrier so as to bring the work into operative engagement with said wheel, reciprocate the work for a predetermined time period while in operative engagement with said wheel, and retract the work from operative engagement with said wheel, one of said switches being closed by said applicator in its home position and the other switch being closed on movement of said applicator from home position.

6. The combination in apparatus as set forth in claim 5, in which said other switch is a time switch being automatically opened a predetermined time period after closure thereof to end an operating cycle of said power means.

7. The combination in apparatus as set forth in claim 5, in which said other switch is a pre-settable time switch being automatically opened a variable time period after closure thereof to end an operating cycle of said power means.

8. Apparatus of the character described, comprising substantially parallel power-driven abrading wheels yieldingly urged toward each other substantially in a first plane in which their rotary axes lie, a carrier for removably holding work with its opposite sides exposed, mechanism for reciprocating said carrier to and from said wheels in a second plane extending transversely of said first plane between, and substantially parallel to the rotary axes of, said wheels, followers movable with said wheels, respectively, in said first plane, and a cam reciprocable with said carrier between and cooperating with said followers to hold said wheels apart throughout the stroke of said carrier and to permit their approach to such an extent only that they follow the desired contours of the adjacent exposed work sides, respectively, as the latter move between and in contact with said wheels, said cam being mounted on said carrier for adjustment in the direction of its reciprocation, said cam comprising two separate cam elements for said wheels, respectively, said cam elements being removably

10 mounted on said carrier for separate adjustment transversely of said second plane.

9. Apparatus of the character described, comprising substantially parallel power-driven abrading wheels yieldingly urged toward each other substantially in a first plane in which their rotary axes lie, a carrier for removably holding work with its opposite sides exposed, mechanism for reciprocating said carrier to and from said wheels in a second plane extending transversely of said first plane between, and substantially parallel to the rotary axes of, said wheels, followers movable with said wheels, respectively, in said first plane, and a cam reciprocable with said carrier between and cooperating with said followers to hold said wheels apart throughout the stroke of said carrier and to permit their approach to such an extent only that they follow the desired contours of the adjacent exposed work sides, respectively, as the latter move between and in contact with said wheels, said cam being mounted on said carrier for adjustment in the direction of its reciprocation, said cam comprising two separate cam elements for said wheels, respectively, said cam elements being removably mounted on said carrier for separate adjustment transversely of said second plane and for common adjustment in the direction of reciprocation of said carrier.
